METHOD FOR MAKING GAS

Charles B. Hillhouse, Newport, R. I., assignor to
Sylvia Remsen Hillhouse, New York, N. Y.

Application October 4, 1930, Serial No. 486,330

3 Claims. (Cl. 48—197)

The invention relates to a method and apparatus for combustion whereby gases of combustion are screened off from materials in the same chamber upon which heat from said combustion is acting, and by a screen which does not materially reduce heat transference.

The invention may be utilized for general purposes or as an improvement in my pending applications Ser. No. 631,778, filed April 13, 1923, Ser. No. 17,565, filed March 19, 1927, and Ser. No. 256,722, filed February 24, 1928, which applications relate to gas producers. The present invention supplies a way of arranging axial combustion, so that the feed of fuel holds the gases of combustion in a defined course through the chamber without materially reducing the heat radiation of the combusting fuel.

The method consists in feeding fuel in sheet form to surround axial combustion and then mixing the fuel current with air from combustion while deflecting them into a flame.

The products of combustion pass axially through the surrounding and moving sheet of fuel, either gaseous, fluid or solid or a mixture of any kind. Oil, or combustible gas free from nitrogen, or other fluid conveyor may be used for the purpose of injecting fuel into the generator or furnace in suitable sheet form, either alone or accompanied by powdered coal or other fuel.

The current of fuel must have sufficient body and velocity to confine the gases of combustion and prevent them from extending into the gas making materials or other materials acted upon.

As the fuel current is strongest at its entrance, while the velocity of the flame may have slackened and expanded at that point, the screen will offer most protection where most needed.

If a hollow circular axial flame is used it will allow inward expansion of the hot gases of combustion as well as expansion outwardly, and will allow combustion taking place nearer the object to which heat is to be transferred, along the walls of the chamber.

This method, among its other advantages, besides confining the gases of combustion to a defined course through the chamber, will preheat the fuel before entering the zone of combustion and will enable combustion to be brought nearer the walls than a usual axial flame.

When pulverized coal is utilized as fuel, air should not be used as its conveying or fluidifying medium, but a non-nitrogenous substance, such as a small percentage of made gas or oil or steam.

In making gas it does not matter whether a

portion of the fuel enters the gas making materials so long as no nitrogen is included in the fuel, nor does it matter whether some of the axial gases of combustion are carried back again into the flame by the fuel current, so they would pass off to the flue with the other gases of combustion, nor does it matter if some of the gas making materials should be drawn into the flame.

Some secondary air, if desired, might enter along the axial line of combustion without danger of unduly expanding the gases of combustion.

Steam (preferably preheated) may be used as a conveying medium and accelerator, as well as a gas or oil under pressure, to bring powdered coal into the gas generator as the principal fuel for axial combustion, and the drawing so indicates it.

Based upon common practice in the use of steam as an accelerator of gases it could be roughly stated that if $\frac{1}{6}$ of the made water gas from 1 lb. of carbon or about 6 cubic feet should be used as the conveying medium for $\frac{1}{2}$ lb. of carbon for axial combustion that about $\frac{1}{4}$ to 1 cubic foot of steam would be enough to give sufficient velocity to the conveying medium to make a suitable protecting screen. The $\frac{1}{2}$ lb. carbon would add but about $1/100$ of a cubic foot to the 7 cubic feet of gas and steam, or a quarter cubic foot, if semi-fluid.

The accompanying drawing shows an application of this method to making water gas, but the screened off hot zone near the furnace walls can be used for other purposes as well.

The drawing also shows a preferred way of having the fuel current travel from top to bottom of the chamber, but the directions of the flame and fuel current could be reversed.

The drawing is a somewhat diagrammatic vertical sectional view of a device for effecting the above mentioned process.

As applied to making water gas this method of combustion may be carried out in the following manner when powdered coal is used as fuel and in gas making.

The base of the apparatus is indicated at 1, and upon the space there is erected an annular wall 2, which is hollow as at 3 so as to permit air from a lead 4, to be heated on its passage down to an inlet 5, into the main chamber 6, of the apparatus. In this main chamber combustion takes place and gas making occurs. The zone of combustion is indicated at 7, and the flue or outlet is indicated at 8. A deflector is indicated at 9, and an air-blower 10.

The inlet 5 for the heated air should be located

in the best position to create downward suction in the deflector 8 on the side of said deflector nearer to the walls 2, and in exact alignment with a circular fuel sheet indicated 11 which fuel sheet 5 moves downwardly into deflector 9, the suction from the incoming hot air maintaining a strong fuel current in the sheet 11. A gas conveying medium, preferably a portion of the made gases or oil is indicated as conveyed by a medium as 12. 10 The steam accelerating and conveying medium, preferably preheated as shown, by 13; and conveying medium for steam for gas making purposes by 14; while 15 is the main source of steam. Powdered coal for fuel is entered thru conduit 16, 15 preferably in a semi-fluid state, as for instance by a Kinyon pump using a portion of made gas instead of air for fluidifying. Powdered fuel in the above semi-fluid condition is caused to run like water from faucets as at 17' as used for chemical 20 requirements in making water gas and for combustion. The gas making materials from 14 and 17 enter the chamber 6 tangentially and made gases indicated at 18, after helically revolving about axial combustion zone 7 leave the gas generator 6 by a tangential outlet 19. The circular sheet of fuel 11 is composed of powdered coal from 17' and conveyed by gas or oil from 12 and accelerated by the steam, preferably preheated, 25 from conveying member 13. Accelerators may be added to the outlets as indicated at 25 and 26. 30 The circular form may be given in various ways to the fuel but the way indicated is to throw downward jets against a circular collar 20. When 35 the circular sheet of fuel 11 reaches the bottom of chamber 6 it enters the deflector 9 where it meets and mixes with heated air from 5 and they are deflected up into combustion zone 7. The circular deflector 9 is built around a truncated cone 21 so 40 as to direct the combusting materials toward the

axial line as indicated by arrows on the drawing.

I claim:

1. The method of producing gas which consists in feeding fuel for combustion in one direction throughout a zone concentric with the axis of a 5 chamber, directing said fuel inwardly and then in a direction opposite to that of the fuel feed and burning the same to form an axial combustion zone extending in an opposite direction to the fuel feed, and feeding carbonaceous material and 10 steam to be gasified along a helical path to surround the fuel feeding zone, and in direct marginal contact therewith whereby the heat from the axial combustion zone is transferred to the gas making materials to convert same into a gas. 15

2. The method of producing gas and screening an axial combustion zone from materials heated thereby, which consists in feeding fuel for combustion along a zone in one direction, deflecting 20 said fuel and burning the same to form a combustion zone extending in an opposite direction adjacent the fuel feeding zone and feeding carbonaceous material and steam to be gasified along a helical path in contact with said zone of fuel feed and separated from the combustion zone by 25 the incoming fuel whereby the heat from the axial combustion zone is transferred to the gas making materials to convert same into a gas.

3. The method of making gas which consists in 30 producing an axial combustion zone in one direction, feeding carbonaceous material and steam to be gasified along a helical path in the opposite direction and parallel thereto, and screening said 35 materials from the combustion zone by feeding the fuel to be burned along an intermediate zone, in marginal contact with said materials whereby the heat from the axial combustion zone is transferred to the gas making materials to convert same into a gas.

CHARLES B. HILLHOUSE. 40
